DESIGN FOR A SANDAL OR SIMILAR ARTICLE

Jacob Stein, New York, N. Y.

Application November 3, 1936, Serial No. 65,662

Term of patent 14 years

To all whom it may concern:

Be it known that I, Jacob Stein, a citizen of the United States, residing in the city, county, and State of New York, have invented a new, original, and ornamental Design for a Sandal or Similar Article, of which the following is a specification, reference being had to the accompanying drawing forming a part thereof.

The figure is a perspective view of a sandal or similar article showing my new design. Both sides of the article are identical.

The sandal shows an upper open at its toe, and having a mesh fabric at said open toe.

The upper part of said upper is made of mesh fabric, to which the ankle closure is connected. Said ankle closure has separate edges, which are connected by a laced cord, which is passed through openings which are located adjacent said edges.

The essential feature of the design is the upper made partly of mesh material and connected to an ankle closure.

I claim:

The ornamental design for a sandal or similar article, substantially as shown and described.

JACOB STEIN.
